UNITED STATES PATENT OFFICE.

MARTIN S. CRANE, OF HOBOKEN, NEW JERSEY.

COUNTER-GUARD BRACKET.

1,112,524.

Specification of Letters Patent.

Patented Oct. 6, 1914.

Application filed September 25, 1913. Serial No. 791,746.

To all whom it may concern:

Be it known that I, MARTIN S. CRANE, a citizen of the United States, and a resident of Hoboken, in the county of Hudson and State of New Jersey, have invented certain new and useful Improvements in Counter-Guard Brackets, of which the following is a specification.

This invention relates to brackets such as are provided for supporting guards of glass or other sheet material for counters, and for protecting counters such as sales counters and the goods thereon.

The object of my improvements is to provide a device of the character specified, simple in construction, and having means for adjusting its several parts relatively to each other for meeting a variety of requirements in this class of goods.

With these ends in view, my improved bracket comprises features illustrated in their preferred form in the accompanying drawings, wherein—

Figure 1 is an end elevation of my improved device. Fig. 2 is a rear elevation corresponding with Fig. 1. Fig. 3 is an enlarged fragmentary view of a portion of what is shown in Fig. 1 and looking at the front thereof. Fig. 4 is a further fragmentary view in perspective illustrating some of the adjustable features of my device. Fig. 5 is another fragmentary view in perspective of a portion illustrating another feature of my device. Fig. 6 is a perspective view of another feature of my device. Fig. 7 is an end elevation similar to Fig. 1 and illustrating a modified form of my improved device.

My improvements comprise a plurality of articulated adjustably interlocking members as 2, 3 and 4, one of which, 2, may be a foot adapted for attachment to counter 5. The lower end of upright member 3 is provided with a face 6 which may be of disk-like form and provided with interlocking means which may comprise a radial rib

7. Foot 2 is provided with an oppositely disposed disk-like face 8 having a plurality of grooves 9 and 10 for coaction, one at a time, with rib 7 on disk 6 of upright 3.

For binding members 2 and 3 together with faces 6 and 8 in engagement, and rib 7 in engagement with one of grooves 9 and 10, I provide disk 6 with a central hole 11 and disk 8 with a central hole 12. Said hole 12 may be provided with a screw thread

for engagement with binding screw 13. Foot 2 may be provided with holes through base 20 thereof for screws 14 which may be screwed into counter 5 to hold said base 60 securely positioned.

Upper end of upright 3 may be provided with interlocking means similar to the interlocking means at its lower end just described. For engagement with the interlocking means at the upper end of upright 3, I provide horizontal member 4, said member 4 being provided with interlocking means similar to that of foot 2 for engagement with the interlocking means at the 70 upper end of upright 3. Said members 3 and 4 are conveniently made of T section, the flat portions thereof being adapted for supporting glass or other plates 15 and 16 respectively.

Plate 15 may comprise two portions 15^a and 15^b meeting in a straight line joint, the medial line of upright 3. For holding said plate portions securely against upright 3, I preferably employ a sheet metal strip 17 80 having holes therethrough for screws 18, 19 and 21. Said plate portions 15^a and 15^b may be chamfered at their corners, as shown in Fig. 3, to permit the passage of screws 18 and 21, and may be notched midway 85 their height for the passage of screw 19.

For holding top plate 16 in position on horizontal members as 4, I preferably provide a metal strip 22, having one end thereof 23 bent into C shape and bifurcated to 90 span rib 40 of member 4, and having the other end bent downwardly in L form and provided with a hole for the passage of screw 21. When said strip 22 is employed in connection with an end bracket and the 95 end of plate 16, I preferably provide downturned ears 24 for retaining said plate in position. In some instances I employ one or more additional horizontal members as 25 for supporting shelves in horizontal position between the counter and horizontal member 4.

Upright 3 and horizontal member 25 may be provided with coacting interlocking means similar to those already described, or 105 said horizontal arm 25 may be bifurcated to span the rib of upright 3 and be held rigidly in place thereon by a pin passing through hole 26 therein and hole 27 in the rib of upright 3, Fig. 6. In some cases I 110 prefer to form members 3 and 4 integral, as for instance, for the reception of a curved

plate 28, Fig. 7. In this case, retaining strip 29 may be of one continuous piece, as illustrated in said Fig. 7, and held in place by screws as already described. It will be obvious to those skilled in the art that said retaining strips 17 and 29 may be comprised of several short pieces of some convenient shape, such as round or square, held on by screws as 18.

10 By my improved device, upright 3 may be supported at different angles relatively to said counter and members as 4, interlocking therewith, in horizontal position or in such other position as is desired. My improved device has the further advantage of mobility in assembling as any one of a variety of heights of member 3 may be assembled with foot 2, and any one of a variety of lengths of member 4 and member 25 may 20 be assembled therewith.

I claim:

1. A counter guard bracket including in combination a fixed foot, an upright member adjustably interlocking therewith, a horizontal member adjustably interlocking with said upright member, and plate retaining means on one or more of said members.

2. A counter guard bracket including in combination a plurality of articulated adjustably interlocking members, said interlocking means comprising a disk-like portion on each member, radial grooves in one disk-like member and one or more complementary ribs on the other disk-like member 30 and means for binding said disk-like members face to face, and plate retaining means on one or more of said interlocking members.

3. A counter guard bracket including in combination a foot adapted for attachment 40 to a counter, an upright member adjustably interlocking therewith, a plurality of horizontal members adjustably interlocking with said upright member, and plate retaining means on one or more of said members. 45

4. A counter guard bracket including in combination a foot adapted for attachment to a counter, an upright member adjustably interlocking therewith, a horizontal member adjustably interlocking with said upright 50 member, and a horizontal member fixed to said upright member between said foot and said adjustably interlocking horizontal member.

5. A counter guard bracket including in combination a fixed foot, an upright member adjustably interlocking therewith and a horizontal member adjustably interlocking with said upright member, said interlocking means comprising a pair of coacting faces, 60 one thereof on each of the interlocking members, one of said faces being provided with interlocking means and the other of said faces being provided with a plurality of interlocking means for engagement with said 65 first mentioned interlocking means, and means for binding said members together in interlocking engagement.

Signed at New York, in the county of New York and State of New York, this 23 70 day of Sept., 1913, before two subscribing witnesses.

MARTIN S. CRANE.
